DESIGN FOR A BOTTLE OPENER

Antonio Paolantonio, Providence, R. I., assignor to Colonial Knife Company, Inc., a corporation of Rhode Island

Application July 12, 1939, Serial No. 85,979

Term of patent 7 years

To all whom it may concern:

Be it known that I, Antonio Paolantonio, a citizen of the United States of America, residing at Providence, county of Providence, State of Rhode Island, have invented a new, original, and ornamental Design for a Bottle Opener, of which the following is a specification, reference being had to the accompanying drawing, forming a part thereof.

Fig. 1 is a plan view in open position of the bottle opener, showing my new design;

Fig. 2 is an edge view in closed position; and
Fig. 3 is a plan view in closed position.
The opposite side of the article is like the side shown.

I claim:

The ornamental design for a bottle opener,
substantially as shown and described.
